CLAIM

The ornamental design for a cooling fan with two air outlets, as shown and described.

DESCRIPTION

FIG. 1 is a perspective view of the cooling fan with two air outlets showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is another perspective view thereof for showing use situation; and,

FIG. 10 is another perspective view thereof for showing use situation.

The dash-dash broken line showing in the figures are for the purpose of illustrating portions of the cooling fan with two air outlets. The additional articles in dash-dash broken line in FIGS. 9 and 10 illustrate environment. None of the dash-dash broken lines form part of the claimed design. The dash-dot-dash broken lines depict boundaries and form no part of the claimed design.

1 Claim, 8 Drawing Sheets
